LOUIS GUENOT, FILS, OF PARIS, FRANCE.

GAS-GENERATING APPARATUS.

SPECIFICATION forming part of Letters Patent No. 794,498, dated July 11, 1905.

Application filed May 12, 1904. Serial No. 207,709.

To all whom it may concern:

Be it known that I, LOUIS GUENOT, Fils, a citizen of the Republic of France, residing at Paris, France, have invented certain new and useful Improvements in Gas-Generating Apparatus, of which the following is a full, clear, and exact specification.

This invention relates to gasogenes; and the present invention, which has for its object to remedy all the inconveniences of prior devices of this nature, consists in the general arrangement of the gasometer and the novel construction, combination, and adaption of parts, all as more fully hereinafter described, claimed, and illustrated in the accompanying drawings, in which—

Figure 1 is a vertical section of the improved device. Fig. 2 shows in elevation the details of the temperature-regulator.

20 A cupola 1, of fireproof masonry inclosed by a casing 2, is provided at its lower part with a grate 3, which is constantly cooled by a basin 4, filled with water. The fuel, which may be of any kind, is put on the grate through 25 the door 5. Two other doors 6 and 7 serve the first to extract the slack and the second the ashes. The doors and the top of the casing have a tight closure. The air which is necessary for the combustion enters through 30 the necks 8 and 9 and the burned gases escape in the stack 10 through the neck 11 after having traversed a first layer 12 of fireproof bricks, which layer is designated as "super-heaters," and a second layer 13 of pieces of 35 iron or castings forming a steam-generator. The water is supplied through a funnel 14, which is twice bent and fixed on the top of the casing. The gas produced passes into a gasometer 15 through the neck 16, after having traversed a receptacle 17, having a hydraulic joint.

Each of the necks 8, 9, and 11 is provided with a valve 18, having a bell 19 and a hydraulic joint. The three bells 19 are fixed by 45 means of rods on a movable frame 20, suspended to one extremity of a beam 21, oscillating on the pivot 22. This beam bears at its other extremity a counterpoise 23 for equilibrium and a little receptacle 24, which 50 communicates by a flexible pipe 25 with an-

other small receptacle 26, disposed on the bell of the gasometer. This latter receptacle is filled with water when the bell is at the lower point of its stroke.

A conduit 27, connected with a suitable 55 source of supply, is provided with a cock 28, which is guided by the beam 21, and the draft of the stack is regulated by the throttle-valve 29, actuated by a regulator of temperature, which is hereinafter described. 60

The apparatus operates as follows: The cupola being filled with ignited fuel and the apparatus being very hot by any well-known way, the beam is brought in the position shown in Fig. 1. The bells 19 of the valves 65 descend into the water and the water-cock 28 is opened, the said bells initially closed before making the run, in any suitable manner. They are entirely closed against the admission of air before making the run, in any suitable manner. They are entirely closed against the admission of air before the water is introduced into the generator. The water flows through the funnel-pipe 14 and drops on the pieces of iron of the steam-generator, where 70 it is transformed into steam. This steam descends across the layer 12 of the superheater and reaches a very high temperature by the contact of the fuel traversed by it. The steam is decomposed by the coal, the hydrogen remains free, and the oxygen unites with the coal to form carbon monoxide. The mixture of these gases traverses the grate and passes into the gasometer 15 through the neck 16 and the trapped receptacle 17. The bell of the 75 gasometer arises rapidly with the little receptacle filled with water, and when the bell is almost at the highest point of its stroke the level of the water in the receptacle 26 is higher than the bottom of the receptacle 24, suspended 80 on the beam. The water passes then through the flexible pipe 25 from one receptacle to the other, and the bell continues to rise until the moment where the receptacle has acquired a sufficient weight for tilting the beam on its 85 pivot, thus actuating the frame 20, which bears the bells 19. The beam stops only when the bells are out of water and impinge against the top of their boxes. Then the receptacle 24 takes the position II. In this new position of 90

100

the beam the cock 28 is closed and no water allowed to flow into the apparatus. The outer air arrives now under the grate by the neck 8 and determines the combustion of the coal; but 5 by reason of the thickness of the layer of fuel the gases of combustion contain besides the carbonic acid a certain quantity of carbon monoxid. A corresponding quantity of air, which may be regulated at will, arrives through 10 the neck 9 above the layer of combustible fuel and brings about the transformation of this carbon monoxid into carbonic acid. The gases of combustion give their heat to the superheater 12 and then to the steam-generator 15. They escape almost cold into the stack. During the period of warming, while no water-gas is produced, the bell of the gasometer 15 descends in correspondence with the consumption. When the bell is almost at the end 20 of its stroke, the bottom of the receptacle 26 becomes lower than the level of the water in the receptacle 24, situated at II. The water passes thus in the receptacle 26, which continues to lower with the bell till the moment 25 where the equilibrium of the beam 21 is broken up by the elevation of the receptacle 24. The beam recovers then its first position, the receptacle rises to the position I, the bells 19 are lowered with the frame 20 and descend 30 again into the water, the cock 28 is opened and permits the water to flow, and the production of gas begins again. The tilting movements of the beam are thus automatically produced so long as fuel is on the grate and gas is taken from the gasometer.

For facilitating the inversions and for decreasing the weight of the water which must pass from one receptacle to the other the bells and the valves may be balanced in the 40 following manner: The sum of the surfaces of the bottoms of the two air-bells is equal to the surface of the bottom of the smoke-outlet bell. On the other hand, the gas contained in the apparatus during the period of production presses from top to bottom on the two first bells and from bottom to top on the third bell. The strains due to the pressure of the gas on these bells are equal and opposed. They compensate naturally one the 45 other, because the three bells are fixed on the same frame 20. This arrangement insures that the beam, being itself balanced by means of a counterpoise 23, may enter in motion by the fact that two or three liters of water pass 50 from one receptacle into the other. The weight of the bell of the gasometer varies thus very little, and the pressure of gas is consequently sensibly constant. If during the working of the apparatus much gas is 55 consumed, the rising of the bell of the gasometer 15 is slow and its descent is rapid. If, on the contrary, little gas is consumed, the rising of the bell is rapid and its descent is slow. Finally, if overconsumption is begun 60 one of the two following facts will be pro-

duced: (a) If the arrest takes place during the period of heating, the bell 15 stops simply in its descending movement. (b) If the arrest takes place during the period of the production of gas, the bell continues to arise, the 70 inversion is produced, and the bell remains lifted until the moment where consumption of gas begins. During this period the apparatus is heated again. It will be seen that never a surproduction of gas can exist, the 75 gas being only produced according to the consumption. To obviate this inconvenience, the throttle-valve 29 in the stack is actuated by a suitable regulator, one form of which is shown in Fig. 2. A minuscule gasometer 30, containing, for instance, about two or three liters of gas, is disposed near the stack of the gasometer and receives some gas by a very small pipe 31. This gas passes in a bulb 33, bent at right angles, and its inferior part, 80 filled with mercury, extends into the stack 10. A pipe 34, which passes through a plug fixed in the bulb or vial 33, touches by its inferior extremity, which is beveled, the mercury. This pipe has on its other extremity a little 85 burner serving as a test. The section of these pipes is such that all the gas flowing into the little gasometer, on the normal working of the apparatus, may easily be emitted by the burner 35. The bell 30 regulates by a device of any 90 kind, similar to the device represented, for instance, in Fig. 2, the throttle-valve 29, so that it is opened largely when the bell is below and completely closed when it is above its stroke. Normally the test-burner 35 burning all the 95 gas brought by the neck 31, the bell remains immobile and the valve 30 opened; but if the temperature increases in the stack of the apparatus the mercury on dilating rises in the vertical part of the bulb 33 and obstructs 100 partly the inferior opening of the pipe 34. The gas being no more able to escape through this pipe is compressed in the bell, which then rises and closes the throttle-valve 29. If the temperature continues to increase in the stack, 105 the bell rises until the throttle-valve 29 is entirely closed. The gas escapes then through a pipe 36, the inferior part of which is brought out of water when the bell is above its stroke, and this gas is ignited on the test-burner 35 110 till the temperature is decreasing in the stack and the mercury is descending again in the vertical part of the bulb. The gas can again escape through the pipe 34. When the bell 115 descends, the inferior part of the pipe 35 dips in the water, the gas turns on the burner 35, and the throttle-valve 29 opens again. In order that the test-burner shall not burn entirely extinct, a hole 37, bored in the pipe 34, permits at all times the gas to pass sufficiently 120 to light the burner as a night-lamp. It will be seen that it is easy to regulate at will the temperature to be obtained in the stack by opening more or less a cock placed in the pipe 31. The heating of the cupola is thus auto- 125 130

matically arrested at the required time by any consumption of gas, and by this fact the gasometer consumes only fuel in proportion to the gas produced.

5 To the gasogene above described, may be joined water-inlets for the replacing of the water coöperated during the working of the apparatus in the vessel of the valve of outlet of smoke and in the basin placed under the grate. To this apparatus may also be joined, if it is desirable, all the appropriated devices of washing, apuration, carburation, and odorization.

The horizontal grate can be replaced by an inclined one easier to clean. The cupola can also be provided with a hopper containing a large quantity of fuel, so that packings are less often required and that the fuel on descending slowly from the hopper on the inclined grate will replace the fuel burned and that a thickness of fuel nearly constant will be maintained on the grate.

What is claimed as new is—

1. A gasogene for the fabrication of water-gas, comprising a cupola, a grate 3 for the fuel, a first layer of fireproof material 12 situated above the grate, and a second layer of iron, forming a steam-generator, this second layer being situated near the upper end of the cupola, the stack 10, the neck 11, the necks 8 and 9, a gasometer 15, for receiving the gas, a receptacle 26, containing water, a receptacle 24, a flexible pipe 25 connecting said receptacles, a beam 21, a frame 20 supported from the other extremity of said beam, three bells 19 suspended from said frame and which can be shifted and which form parts of the valves 18 with hydraulic joint, near the necks 8, 9 and 11, constructed to cause the automatic inversions by means of the ascending and descending movements of the gasometer, which determines the passages of water from one receptacle 26 to the other receptacle 24 and reciprocally at the extreme points of arising and descending of this gasometer and, in consequence, the opening and the closing of the three valves with hydraulic joint, the bells of which are fixed on the frame.

2. A gasogene for the fabrication of water-gas, comprising a cupola, a grate 3 for the fuel, a first layer of fireproof material 12 situated above the grate, and a second layer of iron, forming a steam-generator, this second layer being situated near the upper end of the cupola, the stack 10, the neck 11, the necks 8 and 9, a gasometer 15, for receiving the gas, a receptacle 26, containing water, a receptacle 24, a flexible pipe 25 connecting said receptacles, a beam 21, a frame 20 supported from the other extremity of said beam, three bells 19 suspended from said frame and which can be shifted, and which form parts of the valves 18 with hydraulic joint, near the necks 8, 9 and 11, constructed to cause the automatic inversions by means of the ascend-

ing and descending movements of the gasometer, which determines the passages of water from one receptacle 26 to the other receptacle 24 and reciprocally at the extreme points of arising and descending of this gasometer 70 and, in consequence, the opening and closing of the three valves with hydraulic joint, the bells of which are fixed on the frame, and means for automatically controlling the admission of water by the movements of said beam.

3. A gasogene for the fabrication of water-gas, comprising a cupola, a grate 3 for the fuel, a first layer of fireproof material 12 situated above the grate, and a second layer of 80 iron, forming a steam-generator, this second layer being situated near the upper end of the cupola, the stack 10, the neck 11, the necks 8 and 9, a gasometer 15, for receiving the gas, a receptacle 26, containing water, a receptacle 24, a flexible pipe 25 connecting said receptacles, a beam 21, a frame 20 supported from the other extremity of said beam, three bells 19 suspended from the said frame and which can be shifted and which form parts 90 of the valves 18 with hydraulic joint, near the necks 8, 9 and 11, constructed to cause the automatic inversions by means of the ascending and descending movements of the gasometer, which determines the passages of 95 water from one receptacle 26 to the other receptacle 24 and reciprocally at the extreme points of arising and descending of this gasometer and, in consequence, the opening and the closing of the three valves with hydraulic 100 joint, the bells of which are fixed on the frame and an automatic temperature-regulator.

4. A gasogene for the fabrication of water-gas, comprising a cupola, a grate 3 for the fuel, a first layer of fireproof material 12 situated above the grate, and a second layer of iron, forming a steam-generator, this second layer being situated near the upper end of the cupola, the stack 10, the neck 11, the necks 8, and 9, a gasometer 15, for receiving the gas, a receptacle 26, containing water, a receptacle 24, a flexible pipe 25 connecting said receptacles, a beam 21 a frame 20 supported from the other extremity of said beam, three bells 19 suspended from said frame and which 110 can be shifted and which form parts of the valves 18 with hydraulic joint, near the necks 8, 9 and 11, constructed to cause the automatic inversions by means of the ascending and descending movements of the gasometer, which 115 determines the passages of water from one receptacle 26 to the other receptacle 24 and reciprocally at the extreme points of arising and descending of this gasometer and, in consequence, the opening and the closing of the 120 three valves with hydraulic joint, the bells of which are fixed on the frame, and means for automatically controlling the admission of water by the movements of said beam, and an automatic temperature-regulator. 125

5. A gasogene for the fabrication of water-gas, comprising a cupola, a grate 3 for the fuel, a first layer of fireproof material 12 situated above the grate, and a second layer of 5 iron, forming a steam-generator, this second layer being situated near the upper end of the cupola, the stack 10, the neck 11, the necks 8 and 9, a gasometer 15, for receiving the gas, a receptacle 26, containing water, a receptacle 24, a flexible pipe 25 connecting said receptacles, a beam 21 a frame 20 supported from the other extremity of said beam, three 10 bells 19 suspended from said frame and which can be shifted and which form parts of the valves 18 with hydraulic joint, near the necks 8, 9 and 11, constructed to cause the automatic inversions by means of the ascending and descending movements of the gasometer, which determines the passages of water from one 15 receptacle 26 to the other receptacle 24 and reciprocally at the extreme points of arising and descending of this gasometer and, in consequence, the opening and the closing of the three valves with hydraulic joint, the bells of 20

which are fixed on the frame, and means for 25 automatically controlling the admission of water by the movements of said beam, and an automatic temperature-regulator, and a test-burner.

6. In a device of the character described, 30 the combination of a cupola, a superheater therein, a steam-generator above the superheater, in said cupola, a gasometer, a liquid-trap, a pipe from below the grate into said trap, a pipe from said trap to the gasometer, 35 a liquid-receptacle mounted on the gasometer, a rising and falling receptacle connected therewith by a flexible pipe, a pivoted beam carrying said rising and falling receptacle, and the bells suspended from said beam and the 40 hydraulic necks, all arranged and operating substantially as described.

In witness whereof I have hereunto set my hand in presence of two witnesses.
